CRANE OR DERRICK

Pierre Jean Marie Theodore Allard,
Chantilly, FranceApplication March 1, 1946, Serial No. 651,198
In France September 22, 1943Section 1, Public Law 690, August 8, 1946
Patent expires September 22, 1963

3 Claims. (Cl. 212—50)

1

The invention has for its object a crane or derrick with a grab bucket and automatic sluing of the jib, this sluing being produced when the weight of the full bucket after the latter has been raised is transferred wholly or partly to an auxiliary cable distinct from the latter.

According to the invention the said auxiliary cable which is guided to pass in the neighbourhood of the axis of the pillar or support of the crane passes around a guide pulley carried by the jib at a certain distance from the said axis and is held fixed at its end so that the tension communicated to the said cable by the weight of the bucket between the guide pulley and the fixed point develops a couple producing the rotation of the jib.

Other characteristics of the invention will appear from the following description with reference to the annexed drawing which shows by way of example different embodiments of the invention and in which

Fig. 1 is a diagrammatic elevation of a first embodiment of the invention.

Figs. 2 to 4 are corresponding plan views of the jib in three positions of operation.

Fig. 5 is a view similar to Fig. 1 showing a variant.

Fig. 6 is a view similar to Fig. 4 showing in plan the jib of the crane of Fig. 5.

Figure 7 is a detail of a known construction of the connection between the ring or bell member of the auxiliary cable and the hanging member of the hoisting cable.

Referring to Figs. 1 to 4, 1 designates the post or jib-post of the crane which is mounted so that it can rotate between two pivots 2 and 3 and slopes forwards at an angle α relatively to the vertical. The pivot 3 is secured to a stationary base 5 and the pivot 2 is secured to a buttress 4 which is secured to the base 5. On the post 1 is fixed a two-arm jib 6 supporting at its end a pulley 7 over which passes the lifting cable 8. The cable 8 is guided by a second pulley 9 mounted on the post 1 and winds on to a lifting winch 10. At its free end the cable 8 is fastened to a grab-bucket 11.

On the same shaft as the pulley 7 is mounted a second pulley 12, acting as a guide for an auxiliary cable 12 which then passes over two pulleys 13 and 14 mounted on the post 1 in such a manner that the cable 12 passes substantially through the pivotal axis of the post 1. The cable 12 then passes over a turn-pulley 15 mounted on an extension 16 of the jib 6 so as to be remote from the axis of the post 1, and is then attached to a lateral stationary point 17 of the base 5.

5

At its free end, the auxiliary cable 12 supports a ring 18 adapted to engage a hanging member 18a carried by the grab-bucket 11 in order to enable it to be opened by slackening the lifting cable 8.

10

The connection between the ring or bell-shaped member 18 and the hanging member 18a is diagrammatically shown here because it is a well known and commonly used connection and is clearly exemplified in Figure 1 of French Patent No. 981,298, which is reproduced here as Figure 7, except that the chain of the French patent is here shown as the cable 8 of the accompanying drawings. In this figure, the elements A, B, C, D, correspond to the element diagrammatically illustrated as 18a in Figure 1. The collar F and coupling or flange G correspond to the bell member 18 hooked to the cable 12 in Figure 1.

15

In Figure 7, A represents the head of the grab or bucket 11 which carries two or three shafts H around which pawls B pivot in passing through openings E. These pawls, with their outer portion forming a counterbalance, rest on abutments C of the head A. In the interior of the head A there is a movable slide-block I, also equipped with holes K, whose upper edges rest on the pawls B. The movement of the slide-block inside the head A is limited by the two circular shoulders L and M on the member D. The bell 18, comprising the parts F and G is supported from the auxiliary cable 12 by the jib 6, and it is equipped with three shafts N on which pawls O pivot, these pawls passing through the openings P in the part F and are adapted to hook in under the flange of the slide-block I at one end, while the other end supports a coupling or control flange G along the upper rims of the openings Q made in this flange G. The hoisting cable 8 has a special link R with an abutment S adapted to slide inside the slide-block I to rest on the bottom thereof on a circular protruding base T adapted to hook in under the pawls B when these are in their horizontal position. The pawls B are so mounted as to reduce friction to a minimum.

20

The bell 18 and hanging member 18a cooperate as follows. The loaded bucket is lifted by the cable 8 and as it ascends the head A strikes the bottom of the flange G and lifts it slightly, which results in the release of the pawls O which fall back under their own weight; simultaneously, the slide-block I enters the head F and its flange D passes above the pawls O, after pushing them back while ascending. At this moment the lifting cable is slackened and the

25

bucket remains suspended from the head F by the pawls O. As the bucket opens, the cable 8 is taken up until the special link R rests on the abutment T of the slide-block I, after pushing aside the pawls B which are then returned to their hooking-in position. The cable 8 is slightly taken up again, the special link R strikes under the pawls B and lifts the slide-block I, the upper part of which in its turn strikes the head F while the flange G pushes back the pawls O. The slide-block I is now released from the head and the bucket, which is attached to the cable 8 only by means of the pawls B, can now be lowered. The bucket is rested on the material to be loaded and the cable is slackened; the slide-block I falls back under its own weight, pushing aside the pawls B. The cable 8 is pulled and the link R is not stopped in its upward movement since the pawls B are pushed aside, and the bucket starts closing while going up for a new cycle of operation as described.

It can be seen that by means of this arrangement, when the bucket 11 becomes attached to the ring 18 and its weight is thus transferred from the cable 8 to the cable 12, the tension T (Fig. 3, imparted to the cable 12 and transmitted between the stationary point 17 and the turn-pulley 15 produces a couple tending to rotate the jib 6—16 in the direction F₁.

The device operates as follows:

When inoperative and owing to the forward slope of the post 1, the jib 6 assumes the position of Figs. 1 and 2 corresponding to the pick up point. The winch 10 is then rotated so as to wind up the cable 8, thereby causing the grab 11 to close and then move upwards. At the instant when the hanging member 18a of the grab 11 becomes attached to the ring 18, the cable 8 is slightly slackened and the whole weight of the grab-bucket is thus transferred to the cable 12, the tension of which causes the jib 6 to rotate in the direction F₁ until it assumes the position of Fig. 4 corresponding to the emptying and in which as the pulleys 14 and 15 and the stationary point 17 are in a straight line, the couple produced by the tension of the cable 12 is eliminated.

The slack of the cable 8 is then increased, the grab 11 opens and empties itself. When the grab 11 is empty, the winch 10 is again operated so as to wind up the cable 8 and the weight of the grab is again transferred to said cable 8. As no tension is now exerted on the cable 12, the jib 6 returns to the position of Fig. 2 owing to the slope of its axis of rotation.

The stationary point 17 may be located on either side of the jib 6 according to the direction of rotation which it is desired to give to the jib 6.

In order to retain the jib 6 in any desired angular position, for example in the emptying position of Fig. 4 it is necessary to use a brake, an example of which is shown in Figs. 3 and 4. It comprises a cable 30 which is fixed at both its ends 30a and 30b to the base 5 and which winds a few turns on a loose drum 31 supported by the rear extension 16 of the jib 6. The drum 31 can be braked by a shoe 33 actuated by a pedal or lever 32. When the jib 6—16 rotates, the cable 30 causes the drum 31 to rotate and in order to prevent the jib 6 from rotating when it is in any angular position, it is only necessary to lock the drum 31 by means of the brake 32, 33.

In Figs. 5 and 6 another embodiment has been shown in which use is made, as auxiliary cable,

of an opening cable 12a which, as known, enables the opening of the grab to be controlled at any height of lift.

Said cable 12a passes over the pulleys 13, 14 and 15 which are identical to those of Figs. 1 to 4, and is then returned by passing over a lateral pulley 22 with a stationary shaft, supported by the base 5 and, after passing over a turn-pulley 23, winds on to a drum 19 provided with a counterweight 20 and a brake 21. The counterweight 20 serves to impart constantly a slight tension to the cable 12a, and the brake 21, by locking the drum 19, enables the section of the cable 12a passing over the pulley 22 to be made stationary. It will therefore be seen that when the brake 21 is fully applied, the lateral stationary point of the cable 12a comprises the pulley 22 which performs the same function as the stationary point 17 of the embodiment of Figure 1 and, when the cable 12a is subjected to a pull, enables a couple to be produced which tends to rotate the jib 6—16 and bring the pulleys 14 and 15 into alignment with the pulley 22.

This device operates as follows:

The whole arrangement being in the pick-up position, the winch 10 is actuated so as to wind up the lifting cable 8. The grab closes and moves upwards, the cable 12a simultaneously winding on to the drum 19 by the action 30 of the counterweight 20 which rotates said drum in the winding direction of the cable 12a. When the desired height has been reached, the drum 19 is locked by means of the brake 21 in order to make the corresponding end of the cable 12a 35 stationary and a slight slack is simultaneously given to the cable 8, sufficient for the weight of the grab to be transferred to the cable 12a but insufficient to cause the grab to open. By the action of the pull which is thus exerted on the 40 cable 12a, the jib 6—16 then rotates in exactly the same conditions as in Figs. 1 to 4.

When the emptying point is reached, the jib is locked by means of the brake of Figs. 3 and 4, then the cable 8 is given sufficient slack to 45 produce the opening and the emptying of the grab. The winch 10 is then actuated again in order to wind up the cable 8 while retaining the drum 19 locked. The weight of the grab is transferred to the cable 8 and as the cable 12a is no 50 longer subjected to any tension, the jib 6—16 returns to the pick-up point as in the example of Figs. 1 to 4.

Having now described my invention what I claim as new and desire to secure by Letters 55 Patent is:

1. In a sluing crane, the combination of a frame-work, a pivoting pillar on said frame-work, a jib carried by said pivoting pillar, a hoisting cable passing on pulleys carried by said 60 pillar and jib and adapted to engage with a load to be hoisted, guiding and winding means for said hoisting cable, hanging means secured to said load, an auxiliary cable carrying at one end hooking means adapted to engage said hanging means, means for guiding said auxiliary cable through a point substantially on the axis of said pillar, means for holding the opposite end of said auxiliary cable from a fixed point laterally situated relatively to said axis, and a 65 pulley carried by said jib, remote from said axis and adapted to return said auxiliary cable from said guiding means towards said fixed point.

2. A sluing crane as claimed in claim 1 where-in the load is a grab bucket and said hooking means comprises an opening bell member.

3. A sluing crane as claimed in claim 1 where-
in said means for holding the opposite end of
said auxiliary cable comprises a guiding pulley
carried by said framework at a point laterally
situated relatively to the axis of said pillar and
an auxiliary winch for winding said auxiliary
cable.
